UNITED STATES PATENT OFFICE.

JOHN F. HURLEY, OF DENVER, COLORADO.

WAX-FINISH REMOVER.

1,380,299.

Specification of Letters Patent.

Patented May 31, 1921.

No Drawing.

Application filed July 6, 1920. Serial No. 394,316.

To all whom it may concern:

Be it known that I, JOHN F. HURLEY, a citizen of the United States, residing at Denver, in the county of Denver and State of Colorado, have invented certain new and useful Improvements in a Wax-Finish Remover; and he does hereby declare the following to be a full, clear, and exact description of the invention, such as will enable others skilled in the art to which it appertains to make and use the same.

This invention relates to detergent compositions of the class known as finish removers, and to a process of making them. It appertains more specifically to compositions adapted to remove waxy coatings such as polishes containing a waxy body.

An object of the invention is to produce a composition having the capacity to remove a waxy polish or wax-coating completely and easily without injury to the surface underneath said waxy polish or coating.

It comprises, in general, a process of treating a soap solution with an acid, capable of reacting with the soap, and freeing a portion of the fatty acid, and then adding a small quantity of a soap solvent having also a mild loosening action on a waxy coating; and it also comprises a pasty or gelatinous, semi-liquid composition, resulting from the said process, having the detergent properties of soap, and the property of loosening the waxy polish or other wax-containing surface coating so that it may be completely washed away without destruction of or injury to the subjacent surface. Reference is made to the appended claims, which more particularly point out and distinctly define the process and product comprised in my invention.

It is a common practice to coat floors, furniture, motor or other vehicle bodies, and numerous other objects, with a polish containing some form of vegetable, animal or mineral wax, which may be rendered glossy by friction, and the gloss of which, when dulled by time and atmospheric influence, may be renewed by rubbing with brushes or polishing cloths. Wax coatings are frequently applied over a varnished or painted surface. The presence of a wax polish offers a serious obstacle to repainting or revarnishing, since the paint or varnish will not dry properly when applied over a wax,

and if so applied it quickly loses its luster and tends to crack or check. It is necessary, therefore, to remove all vestiges of wax polish, as well as greasy substances (to which motor vehicle bodies, in particular, are peculiarly exposed) which tend to mingle with it, as an essential preliminary to repainting or revarnishing. It is impracticable to scrape away a wax coating without marring the surface beneath, particularly when said coating is laid over varnish or paint; sand papers and the like become clogged with wax and are not effective, even if their scratchy action were not prohibitive of their use. The known strong alkaline and benzolic removers are unsuitable for use in removing wax coatings applied over paint or varnish where it is desired to retain the foundation coat uninjured.

The composition herein disclosed is adapted to effectively loosen a waxy coating applied over paint or varnish, so that all traces of it may be wiped away, without injury to the underlying coating.

In preparing my wax-coating remover I take a quantity of soap, preferably a hard laundry soap containing sodium oleate, or sodium oleate and stearate, divide it into small parts to facilitate dissolution, and mix it with a quantity of water sufficient to thoroughly dissolve the soap, when heated, but not sufficient to free the fatty acid therefrom. A stronger, even substantially a saturated solution of the soap in hot water is adequate for the purpose of the invention. Having placed the soap in water, the mixture should be heated until all of the soap is dissolved. I have found that approximately one part of soap to four parts of water by weight is a suitable proportion, one half pound of soap dissolved in one quart of water constituting a satisfactory soap solution. During solution the water may be heated nearly or quite to the boiling point.

After the soap has been completely dissolved and while the solution is still hot, a quantity of an acid capable of reacting with the soap should be added to the solution and the mixture of soap solution and acid thoroughly agitated. Although most acids will react with a soap solution, freeing the fatty acids, an acid should be selected that will not produce, as a result of the reaction, a substance injurious to the underlying sur-

face to which the waxy-coating-removing composition is to be applied; also, a quantity of acid should be used such that the whole of the acid will be neutralized in the 5 reaction and some material quantity of soap will remain unchanged. I have found oxalic acid to be most suitable for the purpose, as it and its reaction products with soap do not injure varnish or paint over which the 10 waxy-coating may be applied, and that approximately one part of acid to eight parts of soap by weight will effect the result desired.

The mixture having assumed a gelatinous, 15 pasty or semi-liquid condition as a result of the reaction, is allowed to cool. A small quantity of soap-solvent, having a generally alcoholic action as a wax-coating loosener, is then stirred into the pasty mixture and thoroughly disseminated through 20 it. This soap-solvent may be a finish loosener such as acetone, but is preferably an alcohol. For practical reasons I have used the lower alcohols preferably the denatured 25 alcohol of commerce and have found that about one part of alcohol to eight parts of soap (by weight) constitutes a suitable mixture.

A satisfactory formula for the manufacture 30 of my wax coating remover is as follows:

Eight ounces of laundry soap.
One quart of water.
One ounce of oxalic acid.
35 One fluid ounce of denatured alcohol.
In use the composition may be applied to a waxed surface by means of a brush, damp sponge or the like, and allowed to remain on the surface a sufficient time for it to 40 loosen the waxy material. It should not, however, be permitted to dry. From ten to twenty minutes has been found to be sufficient. Then the surface must be thoroughly washed with water. All of the wax polish 45 or other waxy coating will be removed with the detergent composition.

The fatty acids in the composition are believed to attack the wax, partially dissolve and loosen it from its mechanical hold upon 50 the surface, rendering it soft. The soap partially emulsifies the wax, rendering it susceptible of easy removal, and attacks dirt and grease likely to be found adhering to or mixed in the waxy coating. The alcohol 55 aids in loosening the wax and in dissolving other ingredients of the polish, and has an important function in retarding the tendency of the soap to harden.

When oxalic acid is used with a solution 60 of a sodium soap there will be a sodium oxalate formed as a result of the reaction. The sodium oxalate is supposed to be substantially inert in the composition but probably has a valuable function giving body to the 65 paste.

Owing to the gelatinous state of the composition, it does not run on vertical surfaces but remains long enough to permit it to loosen the coating thereon; it also imprisons the more volatile constituents, retarding 70 their evaporation.

The soap, in addition to its detergent, adhesive and evaporation-retarding properties, 75 renders the composition smooth, easy working and readily removable.

I have found that the described composition will remove all waxy polishes of which I have knowledge.

Having described my invention in the form now best known to me, what I claim 80 and now desire to secure by Letters Patent is:

1. A process of making a wax-coating remover which consists in preparing a strong solution of soap in water, then introducing 85 sufficient weak acid into the solution to react with a portion only of the soap, agitating the mixture, and finally adding a wax-coating loosening material capable of dissolving soap. 90

2. A process of making a wax-coating remover which consists in preparing a strong solution of soap in water, then introducing sufficient weak acid into the solution to react with a portion, only, of the soap, agitating 95 the mixture, and finally adding a relatively small quantity of a lower alcohol.

3. A process of making a wax-coating remover which consists in preparing a strong solution of soap in water, then introducing 100 sufficient oxalic acid to react with a portion, only, of the soap, agitating the mixture, and adding a relatively small quantity of a wax-coating loosening material capable of dissolving soap. 105

4. A process of making a wax-coating remover which consists in adding substantially eight parts of soap to thirty-two parts of water, by weight, heating the water and dissolving the soap therein, introducing into 110 the hot solution substantially one part by weight of oxalic acid, agitating the mixture, allowing it to cool and adding substantially one part by weight of alcohol.

5. A process of preparing a wax-coating 115 remover which consists in adding substantially eight parts of soap containing sodium oleate to thirty-two parts of water by weight, heating the water and dissolving the soap therein, introducing into the hot solution substantially one part by weight of oxalic acid, agitating the mixture, allowing it to cool and adding substantially one part by weight of alcohol.

6. A composition for removing wax-coatings for varnish or other surfaces resulting 125 from the mixture, by weight, of an aqueous solution of substantially eight parts of soap in thirty-two parts of water, with one part of a weak acid capable of reacting with 130

soap, and one part of a generally alcoholic wax-coating loosening solvent capable of dissolving soap.

7. A composition for removing wax-coatings for varnish or other surfaces resulting from the mixture, by weight, of an aqueous solution of substantially eight parts of soap in thirty-two parts of water, with one part of oxalic acid and one part of a generally alcoholic wax-coating loosening solvent capable of dissolving soap.

8. A composition for removing wax-coatings for varnish or other surfaces resulting from the mixture, by weight, of an aqueous solution of substantially eight parts of soap in thirty-two parts of water, with one part of oxalic acid and one part of alcohol.

9. A composition for removing wax-coatings for varnish or other surfaces resulting from the mixture, by weight, of an aqueous

solution of substantially eight parts of soap containing sodium oleate in thirty-two parts of water, one part of oxalic acid and one part of alcohol.

10. A composition for removing wax-coatings for varnish or other surfaces comprising essentially a pasty mixture, by weight, of approximately eight parts of mixed soap and free fatty acid, one part of a soap solvent having a generally alcoholic wax-coating loosening action, and substantially thirty two parts of water.

11. A composition of pasty consistency for removing wax coatings from varnish or other surfaces, consisting substantially of free oleic acid, soap, sodium oxalate, a lower alcohol and water.

In testimony whereof I affix my signature.

JOHN F. HURLEY.
